UNITED STATES PATENT OFFICE.

JOSEPH DESMAROUX, OF PARIS, FRANCE, ASSIGNOR TO COMPAGNIE
GÉNÉRALE AÉROHYDRAULIQUE, OF PARIS, FRANCE.

TEMPERATURE-EXCHANGING APPARATUS.

SPECIFICATION forming part of Letters Patent No. 704,818, dated July 15, 1902.

Application filed December 6, 1901. Serial No. 84,907. (No model.)

To all whom it may concern:

Be it known that I, JOSEPH DESMAROUX, machine-maker, of 4ter Rue des Plantes, in the city of Paris, Republic of France, have

5 invented Improvements in Temperature-Exchanging Apparatus, of which the following is a full, clear, and exact description.

The object of this invention is an improved temperature-exchanging apparatus for permitting two fluids or liquids to exchange completely their temperatures, and chiefly designed to bring back to the normal temperature water which has been brought to an elevated temperature—e. g., 100° centigrade—15 during a suitable time to destroy all the germs that it may contain.

In the improved apparatus the sterilized water at the elevated temperature to which it has been brought resumes the normal temperature, at the same time giving up its heat to the water which is to be sterilized.

The improved apparatus consists, essentially, in two adjacent passages formed by the spiral coiling or rolling of two sheets of metal 25 and by the interposition between these metal sheets of two spiral metal bands the width of which corresponds to that of the passages, these spiral bands being respectively brazed to the opposite borders of the metal sheets, 30 so as to close completely each passage on one face thereof and so that the free openings of these two passages are on two opposite faces of the apparatus.

The two faces of the apparatus are each 35 closed by a plate with a disk of caoutchouc or india-rubber interposed at the joint and serving to insure a fluid-tight closure of the free openings of the two passages.

The special arrangement of the improved 40 apparatus insures an absolute exchange of the temperatures of the two liquids, permits easy cleaning and inspection, and renders impossible any communication between the two liquids.

45 In order that the invention may be readily understood, the improved apparatus is shown in the accompanying drawings in principle, but by way of example only.

Figure 1 shows the apparatus in elevation. 50 Fig. 2 is a vertical section of the apparatus, the plates being removed. Figs. 3, 4, and 5

are horizontal sections on the lines A B, C D, and E F, respectively.

In the figures like letters of reference indicate the same parts.

As shown in the drawings, the improved apparatus is formed by two sheets *a b* of any suitable metal—such as copper, brass, galvanized or tinned iron, &c.—fixed onto a core *c* at two diametrically opposite generating-lines on the said core and rolled around this core, leaving between them a free space having, for example, a width of about five millimeters, and the ends of these sheets of metal are soldered, as shown in Figs. 3, 4, 65 and 5, onto the casing *d* of the apparatus. These two sheets of metal *a b* thus rolled up form the two adjacent passages *e f*. Between these two sheets *a b* of metal are interposed two metal bands *g h*, rolled spirally at the 70 same time as the sheets of metal and brazed onto the opposite borders or edges of the said sheets, so that each passage is completely closed on one side and open at the other and so that the free openings of these two passages are respectively on the two opposite faces of the apparatus.

The apparatus is closed on its two faces by plates *i*, disks *j* of india-rubber or other suitable material being interposed at the joints 80 to insure a fluid-tight closure of the free openings of the two passages. Each plate thus only insures the closure of one passage. The two plates *i* are connected together by bolts *k*.

The entrance and exit of the two liquids 85 which are to exchange their temperatures by their passage through the apparatus is effected for the one part by the openings *l m*, which communicate with the central spaces *n o*, into which respectively open the two passages *e f*, 90 and for the other part by the two tubular pieces *p q* on the external casing *d* at the end of each of these passages. One of the liquids—the cold liquid, for example, the water to be sterilized—enters through the tubular piece 95 *p*, circulates in the direction of the arrows drawn in full lines from the periphery toward the center, and goes out through the opening *l*. On the other hand, the second liquid—the sterilized water to be cooled, for example—100 enters through the opening *m*, circulates in the opposite direction in the direction of the

arrows drawn in chain lines from the center toward the periphery, and goes out of the apparatus through the tubular piece *q*. The sterilized water is thus cooled completely in 5 a closed vessel and issues from the apparatus at a temperature near to that at which the water to be sterilized enters, and this latter goes out at the temperature at which the sterilized water has entered the apparatus. This 10 arrangement insures an absolute exchange of temperature between the two fluids. Moreover, there can never be any communication between the two liquids even if the joints *j* of the apparatus were defective, since if a leak 15 is produced the liquid cannot enter the adjacent spiral passage, since the latter is completely closed by a brazed metal band. Thus it need never be feared with this improved apparatus that the unsterilized liquid will soil 20 the sterilized liquid. Consequently the improved apparatus insures absolute security whatever be the pressure under which the liquids circulate. Moreover, this arrangement enables the apparatus to be easily 25 inspected and cleaned, since it is only necessary to remove the plates *i* in order to see the interior of the two passages.

The improved apparatus can be employed 30 for exchanging the temperatures of two fluids of any kind. It can even comprise a larger number of passages. In this case it is only necessary to roll a number of sheets of metal equal to the desired number of passages.

The form, dimensions, and detail arrangements of the improved apparatus can obviously be somewhat varied according to the different applications thereof.

I claim—

1. A temperature-exchanging apparatus, 40 comprising a cylindrical member provided with two non-communicating spirally-disposed passages, each of a width substantially commensurate with the length of said cylindrical member, one of said passages being 45 normally open at one end of said cylindrical member and the other of said passages being normally open at the other end of said cylindrical member, detachable plates for engaging the ends of said cylindrical members,

thereby closing said passages at said ends, 50 and means for admitting fluids to said passages and for permitting the escape of the same therefrom.

2. A temperature-exchanging device, comprising a cylindrical member provided with 55 a plurality of spirally-disposed non-communicating passages, each of a width substantially commensurate with the length of said cylindrical member, one of said passages being normally open throughout its entire length 60 at one end of said cylindrical member and the other of said passages being normally open throughout its entire length at the other end of said cylindrical member, detachable plates for engaging the ends of said cylindrical members, thereby closing said passages 65 at said ends, and means for admitting fluids to said passages and for permitting the escape of the same.

3. A temperature-exchanging device, comprising a cylindrical member provided with 70 a plurality of spirally-disposed non-communicating passages, each being of a width substantially commensurate with the length of said cylindrical member, one of said passages 75 being normally open throughout its entire length at one end of said cylindrical member, and the other of said passages being normally open throughout its entire length at the other end of said cylindrical member, detachable 80 plates for engaging the ends of said cylindrical members thereby and closing said passages at said ends, means for admitting fluids 85 to said passages and for permitting the escape of the same, and a substantially cylindrical 90 core coaxial with said cylindrical member and provided with two tubular passages parallel with the axis of said member, said tubular passages communicating separately with said spirally-disposed passages.

The foregoing specification of my improvements in temperature-exchanging apparatus signed by me this 21st day of November, 1901.

JOSEPH DESMAROUX.
